BOILER CLEANER

Frederick W. Linaker, St. Louis, Mo.

Application November 28, 1934, Serial No. 755,135

4 Claims. (Cl. 122—392)

My invention has relation to improvements in boiler cleaners and it consists in the novel features of construction more fully set forth in the specification and pointed out in the claims.

The invention is primarily directed to an operating head for actuating the blower tube of a boiler cleaner, and it has for its principal object the control of the steam valve and the rotation of the blower tube with a single actuating mechanism.

It is also the object of this invention to provide an operating head and valve independent thereof, both head and valve, however, being operated by a common actuating mechanism.

It is a further object of the invention to so arrange the valve operating parts and blower tube operating parts that the valve and blower tube may be independently operated if desired, or after having first opened the valve the blower tube may be continuously operated for any desired period while the valve remains open. It is also possible in my improved boiler cleaner to close the valve at any time irrespective of the position of the blower tube in the rotation arc. Thus, there is no definite timed relation between the operation of the blower tube and the operation of the valve, the actuation of these parts being under the control of the operator. The advantage of this selective operation is to make the boiler cleaner universal in its application to boiler cleaners, in that the same apparatus may be used without modification of parts in the various localities in the boiler irrespective of the blowing arc required in each locality.

These advantages, as well as others inherent in the invention, will be better apparent from a detailed description of the same in connection with the accompanying drawings, in which:

Figure 1 is a front view of my improved boiler cleaner; Fig. 2 is a side elevation thereof showing a fragment of the boiler wall on which the operating head is mounted; Fig. 3 is a vertical, middle, longitudinal section taken on the line 3—3 of Fig. 1; Fig. 4 is a vertical cross-section taken on the line 4—4 of Fig. 2; Fig. 4a is a horizontal sectional detail taken on the line 4a—4a of Fig. 2; Fig. 5 is a vertical cross-sectional detail taken on the line 5—5 of Fig. 2; Fig. 6 is a section similar to that shown in Fig. 5 except that Fig. 6 shows the valve actuating mechanism in the position after having actuated the valve; Fig. 7 is a vertical sectional detail through the clutch between the operating sheave and the drive pinion for rotating the blower pipe; Fig. 8 is a section similar to that shown in Fig. 7 except that the clutch elements are in engagement for rotating the blower

pipe; Fig. 8a is a vertical sectional detail taken on the line 8a—8a of Fig. 2; Figs. 9 and 10 are a front elevation and side elevation corresponding to Figs. 1 and 2, respectively, but showing a modified form of the invention; Fig. 11 is a vertical, longitudinal section taken on the line 11—11 of Fig. 9; Fig. 12 is a cross-sectional detail taken on the line 12—12 of Fig. 10; Fig. 13 is a cross-sectional detail taken on the line 13—13 of Fig. 10; Fig. 14 is a view corresponding with that shown in Fig. 12 except that the valve operating mechanism is shown in the position for holding the valve in open position; Fig. 15 is a view corresponding with that shown in Fig. 13 except that the clutch between the operating sheave and drive pinion for the blower tube is shown in engagement; Fig. 16 is a view similar to that shown in Fig. 12 except that the valve operating mechanism is shown in its position just after closing the valve; and Fig. 17 is a cross-sectional detail taken on the line 17—17 of Fig. 10.

Referring to the drawings, A represents the operating head of my improved boiler cleaner shown supported from the wall W of the boiler, the tubes of which are to be cleaned. In addition to the operating head, the boiler cleaner comprises a valve casing 16 and a blower tube 1 passing through an opening 10 in the boiler wall, in which opening is fixed a wall sleeve 2 having a flange 3 to which is secured a plate 4 termed the wall sleeve cap. The wall sleeve cap (in the present instance) is provided with a bracket 5 which carries the operating head A through an adjustable plate 6, coiled spring 7 and saddle member 8. The saddle member 8 has a centrally disposed boss 9 from which projects a stud 10 on which is adjustably positioned a washer 11 by means of a nut 12. The stud 10 passes through the coiled spring 7 and suitable openings 13 and 14 in the plate 6 and bracket 5, respectively, so that the weight on the operating head is resiliently supported by the spring 7. However, the parts just described, including the resilient support for the operating head, are old in the art and will not be further alluded to.

The blower tube 1 is rotatably supported from the boiler tubes (not shown) in any manner now in common use in the boiler cleaning art.

The operating head A and its association with the valve casing 16, together with the actuating mechanism for the blower tube 1, form the subject-matter of the present invention. The head A includes a supporting bracket 15 for the valve casing 16 and valve 17 therein, and the actuating mechanism mounted on the valve casing.

The actuating mechanism for the boiler cleaner is non-rotatory with the exception of the gear 18 for rotating the blower tube 1. Said gear is fixed to a disk 19 formed integral with bracket 15. The bracket 15 is also provided with a ring 20 in spaced relation with the disk 19, on the periphery of which is a channel 21 for receiving the supporting saddle 8. The valve casing 16 has a steam outlet branch 16' provided with a threaded opening 22 in which is screwed one end of a tubular member 23, the other end of said member passing through the ring 20 and having a conical flange 24 formed on it. Between the conical flange 24 and the ring 20 is a bearing element 25 held tightly in place by a coupling member 26, in the threaded opening 27 of which is screwed the threaded end 28 of the blower tube 1. The coupling member 26 is bolted to the ring 20 by a plurality of bolts 29. Thus the bearing element 25 is frictionally held between the bracket 15 and the coupling 26 so that it will rotate with these elements while the tube 23 will remain stationary. In order to make the joint between these movable and stationary parts steam-tight, suitable packing material 30 is packed in the space behind the bearing element 25 and held in place by means of a gland 31 carried by the bracket 15, and maintained in close contact with the packing 30 by means of springs 32 disposed over studs 33 and confined between the gland 31 and a washer 34 held in place by the nuts 35, 36.

The heads 33' of the studs 33 are disposed in sockets s in the disk 19 to prevent the studs from turning, and in order that the pressure of the springs 32 may be directly against the valve casing 16 there are openings o, o through the disk 19 at the bottom of the sockets s in which are inserted short pins or plugs p, p. The outer ends 40 of studs 33 fit loosely in openings r, r in flange 31' of the gland 31 so that the gland is free to move against the packing 30 under the pressure of the springs 32, 32. The operating mechanism for the valve 17 and blower tube 1 will now be 45 described.

The valve casing 16 has a valve cage 37 screw-threaded into a threaded annular shoulder 38 formed in the casing, and the valve 17 operates within said cage within which is formed a bevel 50 valve seat 39. To permit the assembly of the parts the upper threaded part 38' of the cage 37 is formed separately from the lower part of said cage and the two parts are secured together in any desired manner. Ribs 37' on the inner wall 55 of the casing 16 hold the cage 37 in alignment.

A pilot valve 40 traverses an opening 41 in the bottom 42 of cage 37 and is provided with a conical shoulder 43 adapted to rest on a correspondingly shaped valve seat 44 when the pilot 60 valve is closed. Stem 45 extends upwardly from the pilot valve 40 through a stuffing box 46 in valve casing 16 and a perforated flange 47 which serves as a guide for said stem 45. The pilot valve 40 has a port 40' extending from its lower 65 end axially and laterally to open into chamber M within the valve cage 37. Thus when the pilot valve is closed the chamber M will be in communication with the steam supply pipe P and there will be steam pressure within said chamber and against the main valve disk 17. The size of the port 40' is such that when the pilot valve is opened pressure against the valve disk 17 will be relieved so that the valve 17 may be more easily operated.

75 Between the valve housing portion of the cas-

ing 16 and the outlet branch 16' is a steam chamber 48 leading to the tubular member 23, from which the steam passes into the blower tube 1. A bearing bracket 49 projects upwardly from the branch 16' of valve casing 16, said bracket having an outwardly projecting boss 50, through which and the bracket is a bore 51 having a countersunk portion 52 at one end. In the bore 51 immediately adjacent the countersunk portion 52 is a bearing bushing 53, and projecting outwardly from said bore, opposite to the countersunk portion, is a tubular member 54 having an offset portion 54' in which is secured a bearing bushing 55. Thus, the bearing bushings 53 and 55 are in spaced relation and having a shaft 56 mounted within them. The inner end of the shaft carries a pinion 57 partly disposed within the countersunk portion 52 of bore 51, and the outer end of said shaft has an operating sheave 58 loosely mounted on it and held in place by a washer 59 and nut 60 screwed over the threaded extremity 61 of said shaft 56.

The hub 62 of the operating sheave 58 has a clutch element 63 formed on its inner surface for engagement with a clutch element 64 on the collar 65 keyed to the shaft 56 and disposed between said hub 62 and the adjacent end of the tubular member 54. A cam 66 is rotatably mounted on the tubular member 54 and has its cam formation 67 disposed over the valve stem 30 45, between which and the cam element is a lever 68 pivotally mounted to an ear 69 projecting upwardly from the branch 16' of the valve casing 16. From what has just been described it is apparent that the cam 66 is rotatable independently of the shaft 56, but the shaft 56 of course must be rotated in order to operate the pinion 57 and the ring gear 18 with which said pinion meshes. The mechanism for actuating the cam 66 is disposed above said cam and carried on a 40 pin 70 projecting outwardly from the upper part of bearing bracket 49 into which said stem is screw-threaded.

This mechanism comprises a forked lever 71 having arms 72 and 73 in spaced relation and 45 provided with openings 74, 75, respectively, for receiving the pin 70. The lever 71 is loosely mounted on said pin 70 and has an upwardly projecting arm 76 in line with a lug 77 projecting inwardly from sheave 58. A segmental pinion 78 is loosely mounted on pin 70 between the arms 72 and 73 of lever 71, and on the adjacent sides of the pinion 78 and arm 72 clutch elements 79 and 80, respectively, are formed. There are also a series of teeth 81 formed on the cam 66 so that when the pinion 78 is rotated the cam will likewise be rotated.

By referring to Fig. 5 it will be seen that there is 45° of lost motion between clutch elements 79 and 80, and by referring to Fig. 7 it will be seen that there is 180° of lost motion between clutch elements 63 and 64 through which the blower tube 1 is operated. The reason for this will be apparent in the description of the operation of the invention.

The lever 71 has a lug 82 projecting outwardly from the side opposite to the arm 76, which lug operates between a pair of confining fingers 83, 84 loosely mounted on pin 70 and maintained in spaced relation by a spring 85, the ends of which are fastened one to each of said fingers and the coil of which passes around the boss 50 of bearing bracket 49.

Figure 5 shows the relative position of the operating parts when the boiler cleaner is idle, 75

although lug 77 is shown in engagement with arm 76 of lever 71. If the sheave 58 is now rotated in the direction of the arrow (Fig. 5) it will carry the lever 71 around with it, first taking up the 45° of lost motion between clutch elements 79 and 80, after which the pinion 78 will be rotated, in turn rotating cam 66 by virtue of the engagement of the pinion 78 with the teeth 81 of said cam and cause the cam formation 67 to depress the lever 68 and, of course, stem 45 of pilot valve 40. As soon as the pilot valve has been opened to admit steam behind the main valve 17 this valve will also be unseated, causing the steam to flow freely through valve 15 casing 16 into chamber 48 to the blower tube 1. When the lug 77 has traveled to the position shown in Fig. 6 it will release the lever 71, which in the meantime has rocked finger 84 so as to impose the tension of spring 85 thereon, and 20 immediately the lever 76 is released it will be thrown upwardly by the spring tension on the finger 84. However, this backward movement of the lever 76 will not effect the valves as it does not exceed the amount of the lost motion 25 between the clutch elements 79 and 80. The main steam valve thus remains open and a continued rotation of the sheave 58 will rotate shaft 56 and pinion 57 as the lost motion between clutch elements 63 and 64 will by this time have 30 been taken up, as shown in Figs. 7 and 8. The blower tube 1 may now be rotated in the direction of the arrow (Fig. 5) as long as desired without effecting the operation of the valve. After the blower tube has been rotated through 35 a sufficient arc to clean the soot from the boiler tubes the sheave 58 is operated in the reverse direction so that when the lug 77 again encounters the lever arm 76 it will swing said lever back to the position shown in Fig. 5, causing the 40 pinion 78 to rotate the cam 66 to release the lever 68 and valve stem 45 allowing both the pilot and the main valves to close.

In Figs. 9 to 17, inclusive, I show a modification of the invention wherein I employ a somewhat different form of actuating mechanism for the valve and blower element. The manner of supporting the blower tube in the construction of the valve and casing therefor is the same as in the main form. The bearing bracket 49' projecting upwardly from valve casing 16 has a tubular bearing 90 projecting outwardly from it in which shaft 91 is rotatably mounted and on which is freely rotatable a cam lever 92 and sheave wheel 93. Between the sheave wheel 93 and cam lever 92 is a member 94 fixed on the bearing 90 and having an upwardly presented arcuate edge 95. A clutch member 96 having an inner clutch element 97 is fixed on the outer end of shaft 91 and the clutch element 97 is 50 adapted to engage with the clutch element 98 on the adjacent edge of hub 99 of the sheave wheel 93. A cradle 100 is carried on the end of a stud 101 carried in the end of cam lever 92 rotatably mounted on the tubular bearing 90, 55 said cradle having a medially disposed outwardly projecting lug 102 projecting from one side, and a second lug 103 projecting from the opposite side thereof. The ends of the cradle carry pins 104, 104 on which are rotatably mounted rollers 105, 105. A spring 106 is coiled around hub 99 of cam lever 92 and has a pair of arms 107, 107 straddling the stud 101 and bearing on opposite sides of lug 102. The rollers 105, 105 project in the path of the arcuate surface 95 so that 60 they may ride over this surface in the operation

of the blower, as will appear hereinafter. The cam lever 92 has an outwardly projecting lug 92' for the purpose of engaging the end of lever 108 disposed between the cam 92 and the valve stem 45.

Lug 93' projects outwardly from sheave wheel 93 in the path of lug 103 of cradle 100 and engages the lug 103 as the sheave 93 is rotated, as shown in Fig. 12. With a continuation of the rotation counter-clockwise of sheave 93 the leading roller 105 will ride on the arcuate surface 95 as the cam 92 is rotated to cause the cam surface 92'' to depress the lever 108 and valve stem 45. When the main valve is fully open the lug 92' of the cam will engage the end of lever 108 limiting any further movement of the cam lever 92. However, a continuation of the rotation of sheave 93 will tilt the cradle 100 downwardly in the position shown in Fig. 14, allowing the lug 93' to pass the lug 103, after which the force of the spring arms 107 will restore the cradle to its balanced position. The valve now is in its full open position and a continuation of the rotation of sheave 93 will rotate the blower tube by virtue of the clutch element 98 of the sheave 93 impinging on the clutch element 97 secured to shaft 91. The blower tube may now be rotated through any desired arc without in any wise disturbing the valve. However, when the blowing operation is completed and the operator desires to again close the steam valve he will rotate the sheave 93 in the reverse direction which causes the lug 93' to again impinge on the lug 103 and carry the cradle in the opposite direction as it was carried before. This opposite movement of the cradle will of course oscillate the cam lever 92 so as to release the lever 107 and allow the valve stem 45 to rise as the valve 15 is seated.

In both the main form of the invention (Figs. 1 to 8a, inc.) and the modification (Figs. 9 to 17, inc.) I have separated the operating head for the blower tube from the valve mechanism. Therefore, I can use any design of valve mechanism with the head that I may desire. I can also completely replace one valve mechanism with another without disturbing the head or the blower tube.

Having described my invention, I claim:

1. A boiler cleaner comprising a revolvable blower tube, a valve casing communicating with the blower tube, a revolvable support for said casing, a valve in said casing and actuating mechanism carried by the valve casing, said mechanism comprising means for revolving said support including an operating sheave and a clutch between the sheave and the support, and means for operating the valve including a cam, a cam actuating lever, and a clutch between said lever and cam, a driving lug on the operating sheave for oscillating said lever when the sheave is rotated, spring means for maintaining said lever in the path of said lug when not engaged thereby, said clutch between the operating sheave and support having lost motion to cause the actuation of the blower tube to lag behind the actuation of the valve.

2. A boiler cleaner comprising a revolvable blower tube, an operating head including a revolvable support connected to the blower tube, a valve casing in communication with the blower tube, a valve in said casing and actuating mechanism carried by the valve casing, said mechanism comprising an operating sheave, means for revolving said support including clutch elements

between said support and sheave, an oscillating lever effective on the valve to actuate the same, clutch elements between the valve and oscillating lever, a driving lug on the sheave for engaging the oscillating lever, spring means for holding said lever in the path of said lug, said clutch elements between the valve and lever having sufficient lost motion to permit the operation of said spring means, and the clutch elements between the support and sheave having sufficient lost motion to delay the actuation of the blower tube until the valve has been opened.

3. A boiler cleaner comprising a revolvable blower tube, an operating head including a revolvable support connected to the blower tube, a valve casing in communication with the blower tube, a valve in said casing and actuating mechanism carried by the valve casing, said mechanism comprising an operating sheave, means for revolving said support including clutch elements between said support and sheave, an oscillating lever effective on the valve to actuate the same, a driving lug on said sheave for engaging

the oscillating lever, means for releasing said lug therefrom, and means for restoring the lever to the path of said lug, the clutch elements between the support and sheave having sufficient lost motion to delay the actuation of the blower tube until the valve has been opened.

4. A boiler cleaner comprising a revolvable blower tube, a cleaning fluid supply pipe, a valve in communication with the fluid supply pipe, a head mounted on the blower tube, said head including a member to revolve with the blower tube, a stationary tube in said head, said head and stationary tube having swivel connection, means to support the outer end of the blower tube from said revolvable member, means to connect the stationary tube to the valve, and operating means adapted to first open said valve to admit a supply of cleaning fluid to the blower tube while the latter is stationary and afterwards to revolve the blower tube in one direction, said means on reversal adapted to close the valve while the blower tube is stationary.

FREDERICK W. LINAKER.
